UNITED STATES PATENT OFFICE.

GEORGE W. BROWN, OF CAPE ELIZABETH, MAINE.

LEAD PENCIL.

Application filed March 2, 1925. Serial No. 12,736.

- My invention relates to lead-pencils, and more especially to that variety which serves a three-fold purpose,—namely, marking, erasing and sharpening.
- 5 My object is to provide, at a reasonable cost, a practical marking instrument with attachments to perform the functions enumerated above, all mounted on the holder in a compact unit form.
- 10 To accomplish this I have discarded much of the complicated interior works found in many of the present day propelling lead pencils.

I have adopted a frictional lead retaining means to hold the lead firmly in the body or barrel of the pencil, thus eliminating all screws and threads or other expedients to serve as such, and utilize the central plunger as an expulsive means for both lead and 20 eraser. My sharpener is a very simple affair and an essential and convenient acquisition to the pencil user.

Other objects will be apparent from reading the description contained in the specification when taken in connection with the annexed drawings which exemplify one embodiment of my invention, and in which like characters of reference refer to similar parts throughout all the different views.

- 30 In the drawings:
- Fig. 1 is an elevation of my pencil;
  - Fig. 2 is a sectional elevation, taken on a vertical central line through the clip;
  - Fig. 3 is a fragmentary plan view;
  - 35 Fig. 4 is a fragmentary perspective view of the eraser holder and plunger tube;
  - Fig. 5 is a fragmentary perspective view of the forward end of the plunger tube;
  - Fig. 6 is a perspective view of the sharpener;
  - 40 Fig. 7 is a perspective view of the propelling plunger;
  - Fig. 8 is a fragmentary sectional elevation showing the parts in position to expel the lead from the tube;

Fig. 9 is a fragmentary sectional elevation showing the parts in position to propel or feed the rubber out of its container;

Fig. 10 is a cross section through the pencil showing the clip end resting on the flat of the plunger tube;

Fig. 11, the same as Fig. 10, but with the plunger tube turned half way around, and the clip end resting on the round portion of the tube; and

Fig. 12 is an alternative method of mounting the clip end.

Referring to the Figs. 1 and 2, 1 is the body of the pencil, 2 is a collet or chuck tube inserted in the forward, counterbored end of the body. This tube may be secured in the body by any convenient means, as for instance, by the use of glue or other adhesive compounds. The interior bore, 2', of the chuck tube (2), from a spaced distance from the outer end backwardly, is tapered. The pencil body is bored, rearwardly of the chuck tube, as at 1', to a size substantially the same as the straight part of the bore of the chuck tube 2.

Made to easily slide, but with no slack, through the bore 1' of the body 1, is a plunger tube 3, the forward end 4 of which (see Fig. 5) is made tapering to fit the tapered bore of the chuck tube 2. The rearward end 5 of the chuck tube is enlarged and within the enlarged bore 6 is located an eraser 7.

It will be noticed that the plunger tube 3 is flattened at 3', the flat extending from the conical end 4 to the eraser closure 5. A scarf or slot is cut centrally of this flat and for the entire length of same, as at 7', extending through the wall of the tube into its bore 8. This scarf is continued through the conical portion of the tube, but here it is made narrower. There is also a scarf 9 diametrically opposite the scarf 7', extending from the extreme outer end of the tube rearwardly a spaced distance. This is to give the chuck 90 end more resiliency in gripping the lead.

Operating in the bore 8 is the lead 10, abutting on the rearward end of which is the propelling plunger 11, which is also reciprocable within the tube 3. On this plunger (11) is a key 12 which extends through and beyond the scarf 7' and to within a spaced distance of the interior wall of the bore 1'.

Mounted on the body 1 is a clip 13, similar to the conventional type of pencil clip except that at the rearward end there is a bent over portion 14 which normally may rest on the flat 3' of the tube 3.

Should it become necessary to feed the lead forwardly, or in other words propel the lead out of the pencil, the tube 3 is pulled out of the bore 1' of the body sufficiently to allow the portion 14 of the clip to engage the key 12, (see Fig. 8). This acts to force the

plunger forwardly, in its relation to the tube 3 and the lead is forced out from the forward end of the tube.

As has already been stated, the bore 6 provides a space for the eraser 7. As the latter wears away it must be forced out of the bore 6 to allow more of the rubber to be available for use.

The operation of feeding the rubber from its receptacle is performed in the following manner. By observing the Figs. 8 and 10 it will be seen that the square end of the bent over part 14 rests lightly on the flat 3' at the rear of the key 12. The first move is to oscillate the tube 3 one half turn. This brings the part 14 over onto the round portion of the tube 3 (see Fig. 11). In this position the tube 3 may be partially withdrawn from the bore 1, or until the key 12 has passed to the rear of the part 14. The tube is then oscillated back so that the part 14 again rests on the flat 3', but in advance of the key 12 (see Fig. 9). It will be apparent that a movement of the tube 3 forwardly, as indicated by the arrow, will permit the rearward end of the plunger 11 to abut on the eraser 7 and cause it to be forced out of its receptacle 5.

If the next requirement is to feed more lead, the tube 3 may again be oscillated and advanced to such a position as to bring the key 12 forwardly of the part 14, and when these two members are again in line a simple movement of the tube rearwardly will advance the lead and extrude more of it from the tube.

In the construction and operation of the parts as just described the tension of that portion of the clip 13 which supports the part 14 is toward the axis of the pencil. In Fig. 12 I have illustrated an alternative design for this element. In this latter case the tension is away from the axis of the pencil and the end of part 14 is out of contact with the tube 3 and even with the key 12, so that the tube may be withdrawn, advanced or oscillated without interference of the parts 12 and 14, one with the other. But a slight pressure of the finger or thumb on the clip end will bring the part 14 into contact with the key 12,—either in advance or in arrear of it,—and the actuation of the parts carried on similarly to that described in a preceding paragraph.

It is quite important that an eraser should be covered, while not in use, to prevent its becoming soiled and subsequently smearing the work to which it may be applied. I have provided for this by the use of a sleeve 15 which slides over the part 5 and may be locked as against withdrawal by any suitable means, as for instance the well known bayonet lock, as seen at 16,—an indentation 17 being made in the sleeve 15 which enters the open end of the slot 16', advances to the

off-set portion and by a slight turn of the sleeve lands in the locked position.

It might be well to state at this time that the proper method to pursue in operating the chuck is to first give the sleeve 3 a slight twist to the right which releases the hold of the taper fit on the chuck but does not release the bayonet lock on the members 5 and 15. The hold of the chuck being broken, the tube 3 may easily be withdrawn from the body the proper amount. Should the use of the eraser become necessary the sleeve 15 should be turned to the left sufficient to bring the indentation 17 out of the off-set portion of the lock slot, after which the sleeve may be pulled directly off the member 5, exposing the eraser.

It is essential, at times, to have a fine point on the lead to be able to execute certain particular work. I have incorporated in my pencil a sharpening device of simple design and marked efficiency, and this I have illustrated in Fig. 6 of my drawings. It consists of a hardened steel plug 18 cut by a multiplicity of radial scars 18' leaving sharp cutting edges for the pointing of the lead. These scars are V shape with the apex at the point of the lead as it is inserted in the sharpener. This member may be secured in the end of the sleeve 15 by a press fit, or otherwise suitably fixed therein. To operate the sharpener the sleeve 15 is removed from the part 5 and held in one hand while the other grasps the body of the pencil and rotates the lead in the sharpener while the former is rigidly held in the chuck of the pencil.

As previously stated, I have endeavored to do away, in so far as possible to do so, with all positively secured elements in the make up of my pencil. The chuck is wholly dependent on friction to bind the lead in the pencil, but the tapered fit on the chuck is more than sufficient for this purpose; the clip is held to the body by the same means, and gripping is an inherent characteristic of these particular devices; the bayonet locked sleeve, while positively held while in the locked position and with respect to certain movements of the sleeve, is, nevertheless, dependent on the resilient or springlike quality of the split tubular member 5, which is slightly expanded on its outer end for this purpose, to prevent accidental withdrawal should the bayonet lock become released.

In the illustrations and description of the several parts I have shown and described one embodiment of my invention. It is apparent that slight deviations from the exact mechanical construction as herein disclosed might be possible without departing from the spirit and intent of the invention. I shall, therefore, feel at liberty to make such changes as seem to me desirable, in

any of the parts, provided, however, that all such changes shall come within the scope of the appended claims.

What I claim is:

5. 1. In a propelling lead pencil, consisting of a body member, having an axial bore therein and a tapered end, a tube fixed within and for a spaced distance along the bore of said body member, and having a tapered 45 interior converging toward its outer end, a tube reciprocable within said fixed tube and having a straight bore therethrough, an exteriorly pointed end to fit the tapered interior of the said fixed tube, a lateral scarf 50 extending from the end of the tapered portion to within a spaced distance of the opposite end of said tube and an auxiliary scarf diametrically opposite the first mentioned scarf for a spaced distance from the 55 outer end of said tapered portion, a flattened portion on one side of said reciprocable tube, a plunger operable longitudinally of and within said reciprocable tube, a key fixed on said plunger and adapted to extend through 60 and beyond the longer of the two said scarfs, a clip mounted on the exterior of the said body member, a bent over portion on said clip near the rearward end of said body and pointing inwardly, and means for pro- 65 pelling said lead from said pencil by the movement of said reciprocable tube rear- 70 wardly, co-acting with said bent over portion of said clip and said key on said plunger, said key being in advance of said bent over portion.
2. In a propelling lead pencil, consisting of a body member having a central bore therein, a split tube reciprocable within said bore of said body member, and having an 75 externally tapered end, means for compress-
- ing the tapered end of said split tube where- 45 by the bore of same may become contracted, a plunger, reciprocable within said split tube, a key on said plunger, a clip mounted on said body member, a projection on said 50 clip pointing inwardly, an enlarged rearward end on said reciprocable split tube, having a receptacle therein for an eraser, said receptacle being in direct communica- 55 tion with the bore of said split tube, an eraser, and means for expelling said eraser from its receptacle by the movement of said split tube forwardly, co-acting with said bent over portion on said clip and said key on said plunger, said key being in arrear of 60 said bent over portion.
3. In a propelling lead pencil, consisting of a body member, having a central bore therein, a split tube reciprocable within said bore, a flattened side on said split tube, a 65 lead within said split tube, means to contract, diametrically, the outer end of said split tube whereby the lead may be gripped and said tube held against longitudinal movement within said body member, a 70 plunger slideable within said split tube, a key on said plunger extending through and projecting beyond the scarf on said split tube, a projection on said body extending a spaced distance into the bore of the same, 75 means to alternately position said key in advance of and in arrear of the said projection, whereby the oscillation of said split tube combined with the longitudinal movement of the same backwardly and forwardly, co-acting with said projection and said key, may cause said plunger to be moved within said split tube, forwardly and backwardly, respectively.

GEORGE W. BROWN.
